UNITED STATES PATENT OFFICE.

RONALD C. TOLMIE, OF ROCK ISLAND, ILLINOIS, ASSIGNOR TO DEERE & COMPANY, OF MOLINE, ILLINOIS, A CORPORATION OF ILLINOIS.

HAND ANVIL.

Application filed February 9, 1925. Serial No. 7,800

My invention relates to a hand anvil to be more particularly employed in removing and replacing the ledger plates of guard fingers of the cutting apparatus of harvesters.

- 5 Replacement of ledger plates is a frequent necessity, because of damage received in the harvest, for ledger plates are rigidly held in position and the cutter bar, in operation, is in continuous motion, consequently when 10 sticks or stones are caught between a ledger plate and a knife section, the suddenly applied force of such an interruption is destructive, particularly to the ledger plate, and it is exceptional that the latter escapes damage. 15 To remove a damaged ledger plate and substitute for it one in a perfect condition is an exceedingly vexatious operation in the absence of proper tools, and the object of my invention is to provide a hand anvil having 20 a countersink in its face conforming to the shape of the underbody of a harvester guard finger whereby the operation of removing and replacing a ledger plate is facilitated.

Referring to the drawings in which similar 25 numerals indicate identical parts—

Figure 1 is a perspective view of my device.

Figure 2 is a perspective view illustrating the application of my device to one of its uses.

Figure 3 is a reduced sectional view showing 30 my device and the guard finger of a harvester in position for the removal of a ledger plate.

Figure 4 is a plan view of part of the finger bar of a harvester.

35 Figure 5 is a perspective view of a guard finger, and

Figure 6 is a bottom perspective view of Figure 5.

My device is to be used primarily for re- 40 moving worn, damaged or broken ledger plates from the cutting apparatus of a harvester and replacing them with perfect plates, and while this operation is performed by positioning the anvil on the ground or floor beneath the cutter bar of a harvester, it can be utilized with the cutter bar of a mower when the latter is raised and held in a vertical position. The anvil 1 is a cast body with a, preferably, rectangular base in which is a

longitudinal groove 2 and a transverse groove 50 3 to provide a better hand grip and also to lessen the weight of the anvil which otherwise would be excessive.

The face 4 of the anvil 1 has a rearwardly inclined surface for the greater part of its 55 length and has a longitudinal groove 5, which widens and deepens to the end of the incline at which there is a transverse shallow groove 6; from the latter rearwardly the groove 5 increases in width but lessens in depth and 60 the sides thereof are curved, the grooves 5 and 6 conforming to the shape of the underbody portion of a harvester guard finger. Forwardly of the juncture of the grooves 5 and 6 is a vertical opening 7, and forwardly on 65 the face 4, and to one side of the groove 5 is a stud 8, preferably of steel.

When it is desired to remove a ledger plate, the anvil 1 rests on the ground, or on a floor, beneath the guard finger from which the 70 ledger plate is to be removed, the finger 10 resting snugly in the grooves 5 and 6, with the rivet 11 directly above the opening 7, as shown in Figure 3; a punch 12 and hammer 13 are utilized to drive the rivet 11 which 75 drops through the opening 7, freeing the ledger plate so that it can be readily removed; a new ledger plate is then positioned, and a new rivet is inserted, the head of the rivet filling in the opening in the ledger plate, the 80 anvil 1 is then handled to place the stud 8 against the rivet head where it is firmly held until the end of the rivet, projecting below the guard finger, is upset by use of a hammer so that the new ledger plate is rigidly 85 secured in position.

My device is simple, economical, and of convenient size to be carried into the field as part of the tool equipment of a harvester.

What I claim is—

1. A hand anvil having a longitudinal and a transverse groove in its face, the longitudinal groove widening and increasing in depth toward the transverse groove, and a vertical hole through the anvil adjacent the intersection of said grooves. 95

2. A hand anvil having a longitudinal and a transverse groove in its face, the longitudi-

nal groove widening and increasing in depth toward the transverse groove and decreasing in depth rearward therefrom, and a vertical hole through the anvil adjacent the intersection of said grooves.

3. A hand anvil having a longitudinal and a transverse groove in its face, the longitudinal groove widening rearwardly, a vertical hole in the anvil adjacent the intersection of

said grooves, and a stud in the face of the 10 anvil to one side of the center thereof.

4. A hand anvil having a longitudinal groove in its face widening toward one end, a vertical hole through said anvil intermediate the length of the groove, and a stud projecting from the face of the anvil at one side of the groove.

RONALD C. TOLMIE.
